MACHINE FOR APPLYING EDGE-BINDING STRIPS

Thomas J. Doyle, Lynn, Mass., assignor to United Shoe Machinery Corporation, Borough of Flemington, N. J., a corporation of New Jersey

Application September 21, 1937, Serial No. 164,918

30 Claims. (Cl. 12—17)

This invention relates to machines for applying edge-binding strips and is herein illustrated as embodied in a machine for applying an adhesively coated binding strip to the edge and adjacent margins of a piece of work, such, for example, as an insole.

In the manufacture of shoes such as those known as strap sandals, the edge of the insole would be exposed in the completed shoe were it not covered by a binding strip of decorative material which commonly has been secured in position by stitches passing through the insole and the edges of the strip. It is difficult to cause stitched strips to fit tightly and without wrinkles and with some insoles, the stitching is very difficult. In order to improve the appearance of the work and to make it possible to get a tightly bound edge on work which varies in shape or thickness around its periphery, it has been proposed that the binding strip shall have one face provided with an adhesive of the type used on surgeon's tape so that the strip may be wrapped around the edge of the work and be attached thereto smoothly and firmly by means of the adhesive carried by the strip. In the application of such adhesively coated strips, it is essential that the outer marginal portions of the strip shall be brought into contact with the margins of the work piece after the inner portions have been stuck since, otherwise, an edge of the strip might contact with a portion of the work nearer the peripheral edge than is desired and a wrinkle formed in the strip. Commonly, the binding material employed is formed from a bias textile strip which will stretch as the binding is applied to a sharply curved portion of the periphery of the work, thus enabling the strip to be laid smoothly on the work without the formation of puckers or wrinkles.

Accordingly, an object of the invention is to provide a machine for applying a binding strip which will be suited for the application of an adhesively coated strip and enable the binding to be applied smoothly and quickly.

In order that the adhesively coated binding may be applied smoothly across the margin of the work, the machine, in accordance with a feature of the invention, is provided with means operating progressively across the margin, i. e., crosswise of the edge of the work, and acting to press the binding into contact with the work first at the inner margin adjacent to the edge of the work piece and then progressively toward the outer margin. As illustratively described, two forms of binding pressers have been employed,

one of which is a rocking member positioned transversely of the margin where the strip is to be applied and arranged to contact first with the corner of the work and then to tilt toward the inside of the work. Another pressing device, herein shown as operating on the lower margin of the work, is intermittently reciprocated transversely of the margin. The work of these pressers is facilitated in the illustrated machine by providing a guide which bends the binding material from a flat condition into an open channel shape. The edge of the work is pressed against the mid-portion of the strip as it rests in said guide and, as illustrated, the work is moved progressively through the machine by means of work-feeding mechanism, herein shown as of the oscillating-gripper or hammer-and-anvil type.

In order to be able to control the widths of the margins of the strip applied to the upper and lower faces of the work, provision is made, in accordance with another feature of the invention, for supporting the work at just the desired level with respect to the grooved strip-guide. As illustrated, this work support has an overhanging upper end which projects into the channel of the strip which has been formed by the grooved guide and provision is made for controlling the height-wise relation of the table and guide. Preferably, the under side of the work support is beveled in the direction of the natural bend of the binding as it is applied to the work to avoid any scraping action on the coated surface of the binding strip. Operation of the machine is facilitated in the illustrated arrangement by placing the upper binding presser over the work table to bring one margin of the strip into firm engagement with the work. The other binding presser is positioned just beyond the work table, considered with reference to the direction of movement of the work, and, in order that it may press the binding into firm engagement with the work, the upper presser has an extension forming an abutment which lies above the work directly opposite this lower presser.

These and other features of the invention will be best understood from a consideration of the following description, taken in connection with the accompanying drawings, in which

Fig. 1 is a side elevation of an illustrative machine with a side cover removed and a portion shown in section;

Fig. 2 is a horizontal section on the line II—II of Fig. 1;

Fig. 3 is an end elevation of the machine with an end cover removed;

Fig. 4 is a vertical transverse section through the machine on the line IV-IV of Fig. 1.

Fig. 5 is a horizontal section through the machine on the line V—V of Fig. 1;

Fig. 6 is a view of part of the operating mechanism removed from the frame and viewed as from a section line VI—VI in Fig. 1:

Fig. 7 is a side elevation of this same mechanism with parts in section, and

Fig. 8 is an angular view of this same mechanism and other operating parts removed from the frame.

The machine is built in a frame casting 10 in which there is journaled a drive shaft 12, this

The machine is built in a frame casting 10 in which there is journaled a drive shaft 12, this frame being provided with a central cavity 14 normally closed by a side cover 16 and an end cavity 18 (Fig. 5) normally closed by an end cover 20. Within these cavities 14 and 18 are arranged operating parts to actuate tools for pressing a precoated adhesive binding strip 22 around the edge of an insole 24 and for feeding the work along so that the binding is laid progressively about the periphery of the insole and the adjacent margins of the substantially parallel flat surfaces thereof. During the progress of the work through the machine, the insole is rested on a work support or table 26 adjacent to which there is a grooved guide 28 having a throat 30 which is roughly V shaped (Fig. 1) but in which the V has a flat bottom. The binding is drawn around the corner and through the open throat of this guide, being thereby given a sort of open channel of V shape. The under side of the table 26 is beveled in two directions at 27 (Fig. 3) and 29 (Fig. 8) along the direction of the natural bend of the strip to avoid the binding strip and to allow it to run smoothly.

15 and another similar one, to be described later, are received in a groove 56 extending vertically of a web 58 which is integral with the frame 10.

15 The arrangement of this presser lever 38 is such that the rocking presser 34 contacts first with the binding where it rests on the upper, outer corner of the insole supported on the table and then rocks about this corner so as to press the upper portion of the binding progressively, widthwise from the inner to the outer margins thereof, into contact with the work. In so doing, the pivot 40 is raised slightly, thereby rocking the plate 42 about its fixed axis 44 and this takes place against the tension of a spring 60 surrounding a bolt 62 which is pivotally attached by a pin 64 to a portion of the plate 42, the latter being substantially triangular in shape. The spring 60 is confined between nuts 66 at the bottom of the bolt 62 and a guide block 68 received in a recess 70 (Fig. 5) in the side cover 16. This guide block is releasably attached to the cover by means of an integral bolt 72 having a nut 74. It will be seen from Fig. 1 that the bolt 62 is substantially smaller than the opening of the guide block 68 and that it is provided with a guide sleeve 76 threaded on the

20

30

35

The peripheral edge of the insole will be pressed by the operator against the binding where the latter is opposite and, hence, supported by the abutment surface 32 at the bottom of the throat of the guide 28 and thereafter the binding will be applied by the machine to the margins of the upper and lower surfaces of the insole, respectively, by an oscillating presser 34 and a reciprocating wiper 36. The presser 34 is rocked about an axis parallel to the line of feed, the axis here being at the upper corner of the insole, so that the binding is brought down into contact with the upper surface of the insole progressively from the inner margin of that portion of the binding which is adjacent to the insole periphery to the outer margin of that portion of the binding, it being understood that the binding material is a bias braid and is stretched sufficiently at the sharply curved portions of the insole by a tension applied to the binding by any suitable means (not shown) so that there will be substantially no pleats visible on the upper and lower surfaces. At substantially the same time, the reciprocating wiper 36 carries the lower portion of the binding progressively into contact with the margin of the lower surface of the insole. The action of these devices, that is, the presser 34 and the wiper 36, is intermittent and takes place during the backward or idle movement of an oscillating feed mechanism to be described later. The table 26 functions as a stationary anvil and cooperates with the wiper 36 to support the work for the action of the presser 34.

The rocking presser 34, having a portion above the table 26 and another portion above the wiper 36 (Fig. 3), is carried on a lever 38

which is pivotally connected at 40 to a plate 42, this plate being resiliently biased to a predetermined normal position and swiveling about a pin 44 which is secured in an outstanding boss

pin 44 which is secured in an outstanding boss 5 46 (Fig. 5) formed integrally with the frame 10 within the cavity 14. The lever 38, protruding through an opening 39 (Fig. 4) in the frame, is oscillated by means of a crank 48 on the drive shaft 12 on which there is mounted a pitman 50 10 connected by a pin 51 to a slide 52 which is joined, in turn, to the lever 38 by a link 54. This slide and another similar one, to be described later, are received in a groove 56 extending vertically of a web 58 which is integral with the frame 10

15 The arrangement of this presser lever 38 is such that the rocking presser 34 contacts first with the binding where it rests on the upper, outer corner of the insole supported on the table and then rocks about this corner so as to press 20 the upper portion of the binding progressively, widthwise from the inner to the outer margins thereof, into contact with the work. In so doing, the pivot 40 is raised slightly, thereby rocking the plate 42 about its fixed axis 44 and this 25 takes place against the tension of a spring 60 surrounding a bolt 62 which is pivotally attached by a pin 64 to a portion of the plate 42, the latter being substantially triangular in shape. The spring 60 is confined between nuts 66 at 30 the bottom of the bolt 62 and a guide block 68 received in a recess 70 (Fig. 5) in the side cover 16. This guide block is releasably attached to the cover by means of an integral bolt 72 having a nut 74. It will be seen from Fig. 1 that 35 the bolt 62 is substantially smaller than the opening of the guide block 68 and that it is provided with a guide sleeve 76 threaded on the upper portion of the bolt and held in adjusted position there by a lock nut 78.

40 The reciprocating wiper 36, by which the binding is applied to the lower surface of the work, is formed at the end of a rod 89 slidable within a rib 82 forming part of the frame and is held against rotation by a block 84 which is attached thereto by a set screw 86 and one side of which rests against a vertical surface of a boss 83 forming part of the frame casting. The operative portion of the wiper 36 has a rounded corner 90, as may be seen in Fig. 4, in order to reduce the friction of the binding material thereagainst when the work is fed and this wiper is reciprocated in time-relation to the presser 34 by means of a crank 92 having a pitman 94 which is pivotally attached at 96 to a slide 98 lying beside the slide 52 in the groove 56. The presser 34 and the wiper 36 complete their work-contacting movements at substantially the same time. This slide 98 communicates its movement to the rod 89 through a bell crank 100 pivotally mounted on the frame by means of a pin 102 at its mid portion and having its upper and lower arms connected to the block 84 and the slide 98, respectively, by sliding blocks 104 and 106 received in rectangular recesses therein.

65 An intermittent feeding movement is imparted to the work by a feed mechanism of a well-known type embodying upper and lower grippers 110 and 112 which grasp the bound edge of the insole and carry it forward a short distance and then 70 open and return for a new engagement with the insole during the time when the latter is gripped by the presser 34 and the wiper 36. To this end, the upper gripper 110 is formed as an overhanging portion at the top (Fig. 7) of a slide 114 received in an inner groove 116 (Fig. 5) of a swing-

ing arm 118, the lower end of which is pivoted on a reduced portion 120 of the drive shaft 12. The lower gripper 112 is attached to the swinging arm 118 by means of a screw 122. Two movements are imparted to the grippers, one by reciprocating the slide 114 in the arm 118, and this is done by a crank 124 at the very end of the drive shaft which is connected by a pitman 126 to a block at the lower end of a rod 128 passing through an aperture in a foot 130 at the bottom of the slide 114. Above this foot, the rod 128 is surrounded by a spring 132 held under tension by a block 134 pinned to the upper end of the rod and slidably received in a groove 136 at the front of the swinging arm 118. This spring 132 allows for variations in the thickness of the work and causes the upper gripper 110 to be resiliently pressed against the previously applied binding, thereby, in cooperation with the lower gripper 112, to hammer the binding into firm contact with the opposite sides of the insole. The feeding component of the movement of the grippers is imparted by rocking the arm 118 about the drive shaft 12 and this is effected by a crank 140 formed on said shaft and communicating its movement through a pitman 142 to a lever 144 which rocks about a fixed pin 146 supported on the frame 10 (Fig. 1) at the rear of the recess 18. The upper end of this lever 144 is connected by a link 148 to an ear 150 on a side of the swinging arm 118.

During the operation of the machine, a supply of binding under suitable tension and drawn over the guide block 28 is formed into an open channel into which the periphery of the insole 24 is pressed. The binding is then pressed against the upper and lower sides of the insole. This latter action is accomplished by the presser 34 above the work where it rests on the table 26 and the wiper 36 below the work at a point opposite the abutment portion of the presser 34. The insole is fed intermittently past the operating tools by feed mechanism comprising the grippers 110 and 112 which engage the upper and lower sides of the applied binding and press or hammer it firmly into engagement with the work as they intermittently grip the work and move it forward, i. e., in the direction of the feed movement.

Having described my invention, what I claim as new and desire to secure by Letters Patent of the United States is:

1. In a machine for applying an adhesively coated edge-binding strip, a grooved guide for the binding strip against which the edge of the work may press the strip to cause it to adhere to said edge, and means associated with the upper and lower faces of the work respectively for intermittently pressing the margins of the strip into contact with the margins of the work.

2. In a machine for applying an adhesively coated edge-binding strip, a grooved guide for the binding strip against which the edge of the work may press the strip to cause it to adhere to said edge, means associated with one face of the work for intermittently pressing a margin of the strip into contact with a margin of the work, and a coacting hammer-and-anvil mechanism forward of said intermittent pressing mechanism for engagement with the bound edge of the work.

3. In a machine for applying an adhesively coated edge-binding strip, a grooved guide for the binding strip against which the edge of the work may press the strip to cause it to adhere to said edge, and driven means associated with

the upper and lower faces of the work respectively for pressing the extreme margins of the strip into contact with the margins of the work after the inner portions of the width of the margins have been pressed into contact with said upper and lower faces of the work.

4. In an apparatus for securing edge binding to shoe soles, a stationary anvil, a hammer, mechanism for rapidly reciprocating the hammer with respect to the anvil, and a tape-folding device for delivering between the hammer and anvil an adhesive-coated tape in folded relation upon the marginal edge of the shoe sole.

5. In a machine for applying an adhesively coated edge-binding strip, a grooved guide for the binding strip against which the peripheral edge of the work may press the strip to cause it to adhere to said edge, and cooperating binding-applying members at least one of which moves progressively across the margin of the binding strip.

6. In a machine for applying a binding strip, a grooved guide for the binding strip, and an intermittently acting binding presser movable transversely of the edge of the work and arranged to press against the binding from the periphery of the work inwardly of the margin thereof.

7. In a machine for applying a binding strip, a guide for the binding strip having a recessed throat, and a binding presser constructed and arranged to rock about the peripheral corner of the work.

8. In a machine for applying a binding strip, a binding guide, a yielding support, and a rocking presser member pivotally mounted on said support for carrying one margin of the strip into engagement with one margin of the work.

9. In a machine for applying a binding strip, a binding guide, a pivoted support which is resiliently biased to a normal position, and a rocking presser member for carrying one margin of the strip into engagement with one margin of the work, said presser member being pivotally mounted on said pivoted support.

10. In a machine for applying a binding strip, a grooved guide for the binding strip to partially fold it, a work support having a work-engaging end projecting into the bend of the partially folded binding, a rocking presser member cooperating with the portion of the binding which is on the side of the work not engaged by the work support, the presser member being positioned opposite the work support to cooperate therewith in pressing the binding strip against at least one side of the work, and means to urge the presser member against the binding.

11. In a machine for applying a binding strip, a grooved guide for the binding strip, a work support having its upper end projecting into the binding partially folded by the guide, and a presser member cooperating with the portion of the binding which is above the work, the presser member being positioned opposite the work support to cooperate therewith and operating progressively across the margin of the work.

12. In a machine for applying a binding strip for attachment by means of adhesive, a guide for folding the strip about the edge of the work and provided with an abutment against which the work may press a mid-portion of the binding strip, and a hammer-and-anvil feed for engagement with the bound edge of the work comprising an anvil and a hammer carried by said an-

vil constructed and arranged to apply pressure to press the binding against the work as it feeds the latter.

13. In a machine for applying a binding strip, a guide for the binding strip having a recessed throat, and means for wiping the strip progressively across the margin of one face of the work into firm contact therewith.

14. In a machine for applying a binding strip, a guide for bending the strip into a channel shape, and a wiper reciprocable transversely of the margin of the work for pressing a portion of the strip progressively into engagement with said margin.

15. In a machine for applying a binding strip, a guide for bending the strip into a channel shape, and a wiper reciprocable transversely of the margin of the work for pressing a portion of the strip progressively into engagement with said margin, said wiper having a rounded corner at the side toward which the binding approaches the wiper.

16. In a machine for applying a binding strip, a grooved guide for the binding strip to fold the strip partially around the edge of the work, a work support, and intermittently operated means positioned beside said work support for pressing a portion of the binding into engagement with the margin of the work which has passed over the work support.

17. In a machine for applying a binding strip, a grooved guide for the binding strip to fold the strip partially around the edge of the work, a work support, and intermittently operated means positioned beside said work support for pressing a portion of the binding into engagement with the margin of the work which has passed over the work support, said means wiping the strip progressively across the margin of the work.

18. In a machine for applying a binding strip, a grooved guide for the binding strip to fold the strip partially around the edge of the work, a work support having a portion projecting into the channel of the partially folded strip, and intermittently operated means acting transversely of the margin of the work for pressing a portion of the binding into engagement with the work as it is supported on the work support.

19. In a machine for applying a binding strip, a grooved guide for the binding strip to fold the strip partially around the edge of the work, a work support having a portion projecting into the channel of the partially folded strip, intermittently operated means positioned beside said work support for pressing a portion of the binding into engagement with the margin of the work which has passed over the work support, and other pressing means operating transversely of the margin and positioned above said work support and said first-mentioned presser means to coact therewith.

20. In a machine for applying an adhesively coated edge-binding strip, a grooved guide for the binding strip for bending the strip into a channel form, a work support adjacent to said guide, means associated with the upper and lower faces of the work respectively for pressing the margins of the strip into contact with the margins of the work progressively across said margins, and supporting means for said work support and said guide permitting relative heightwise adjustment thereof to enable control of the widths of the margins of the applied strip.

21. In a machine for applying an edge-bind-

ing strip for attachment by means of adhesive, a guide for bending the binding strip into a channel form and constructed and arranged to operate on work having an irregular edge contour, a

5 work support adjacent to said guide, supporting means for said work support and said guide permitting relative heightwise adjustment thereof, and work-feeding means constructed and arranged intermittently to press the margins of the strip into contact with the margins of the work.

22. In a machine for applying a binding strip, a grooved guide for forming the binding strip into a channel shape, a work support positioned alongside said guide and having an overhanging upper end projecting into the channel of the binding strip, the under side of said work support being beveled outwardly and rearwardly to avoid the binding as it is applied to the work, and means for applying the binding to the margins of the upper and lower faces of the work.

23. In a machine for applying an edge-binding strip for attachment by means of adhesive, a guide for folding the strip partially around the edge of the work, a work support, and a member co-operating with said work support to press a margin of the strip into contact with a margin of the work, said member being arranged for rocking movement about an axis substantially parallel to the direction of movement of the work thereby to engage the binding strip near the edge of the work before it engages the inner portion of the binding strip.

24. In a machine for applying an adhesively 35 coated edge-binding strip, a grooved guide for the binding strip, means for feeding the work intermittently, and means positioned between the feeding means and the guide and associated with the upper and lower faces of the work respectively for intermittently pressing the margins of the strip into contact with the margins of the work.

25. In a machine for applying an adhesively 45 coated edge-binding strip, a grooved guide for the binding strip against which the edge of the work may press the strip to cause it to adhere to the peripheral edge of the work, means for feeding the work past the guide, and means associated with the upper and lower faces of the work respectively for pressing the strip progressively across the margins to bring the strip into engagement first with the outer portions of the margins of the work adjacent to the edge and then progressively into engagement with the inner portions of the margins.

26. In an apparatus for securing an edge binding to shoe soles, an anvil, a hammer, mechanism for rapidly reciprocating the hammer with respect to the anvil including a yielding mounting 60 for the hammer to limit the blow delivered thereby, and a tape-folding device for delivering between the hammer and anvil an adhesive-coated tape in folded relation upon the marginal edge of a shoe sole.

27. In an apparatus for securing an edge binding to shoe soles, an anvil member, a hammer member, mechanism for rapidly reciprocating the hammer member with respect to the anvil member, one of said members having a yielding mounting to limit the blow delivered by the hammer member, and a tape-folding device for delivering between the hammer and anvil an adhesive-coated tape in folded relation upon the marginal edge of a shoe sole.

28. In an apparatus for securing an edge binding to shoe soles, an anvil, a hammer, mechanism for reciprocating the hammer with respect to the anvil including a yielding member to limit the blow delivered by the hammer, and a tape-folding device for delivering between the hammer and anvil an adhesive-coated tape in folded relation upon the marginal edge of a shoe sole.

29. In an apparatus for securing an edge binding to shoe soles, an anvil member, a hammer member, mechanism for reciprocating the hammer member with respect to the anvil member, a yielding element associated with one of said members to limit the blow delivered by the hammer member, and a tape-folding device for delivering between the hammer and anvil an ad-

hesive-coated tape in folded relation upon the marginal edge of a shoe sole.

30. In a machine for applying an adhesive-coated binding strip to the edge and adjacent margins of an insole, a grooved guide for folding a binding strip about the edge of an insole presented thereto and against which guide the edge of the insole may press the strip to cause it to adhere to said edge, and means associated with the upper and lower faces of the work respectively, for intermittently pressing the margins of the strip into contact with the margins of the insole, said means including a yielding member for limiting the pressing action upon the margins of the strip.

THOMAS J. DOYLE.
